(57) **CLAIM**

The ornamental design for an imaging apparatus, as shown and described.

DESCRIPTION

FIG. 1 is a rear-right perspective view of an imaging apparatus according to the present invention.

FIG. 2 is a front view of the imaging apparatus.

FIG. 3 is a rear view of the imaging apparatus.

FIG. 4 is a right side view of the imaging apparatus.

FIG. 5 is a left side view of the imaging apparatus.

FIG. 6 is a top view of the imaging apparatus.

FIG. 7 is a bottom view of the imaging apparatus.

FIG. 8 is a sectional view of the imaging apparatus along 8-8 in FIG. 4.

FIG. 9 is a sectional view of the imaging apparatus along 9-9 in FIG. 5.

FIG. 10 is an enlarged view of the encircled portion of FIG. 4; and,

FIG. 11 is an enlarged view of the encircled portion of FIG. 9.

The dash-dash broken lines in FIGS. 1-9 illustrate portions of the imaging apparatus that form no part of the claimed design.

The dash-dot-dot-dash broken lines in FIGS. 4 and 5 showing the sectional lines and the encircled portions of the imaging apparatus form no part of the claimed design.

The right side view of the handle of the imaging apparatus shown in the enlargement of FIG. 10 is mirror symmetrical to the opposite side view thereof.
